UNITED STATES PATENT OFFICE

HAROLD B. DONLEY, OF COLUMBUS, OHIO

DESIGN FOR A PILLAR LAMP FOR MOTOR VEHICLE BODIES

Application filed October 18, 1932. Serial No. 45,402. Term of patent 7 years.

To all whom it may concern:

Be it known that I, HAROLD B. DONLEY, a citizen of the United States, residing at Columbus, in the county of Franklin and State of Ohio, have invented a new, original, and ornamental Design for a Pillar Lamp for Motor Vehicle Bodies, of which the following is a specification, reference being had to the accompanying drawing, forming a part thereof.

Figure 1 is a perspective view of the lamp showing my new design, and

Figure 2 is a top plan view thereof.

I claim:

The ornamental design for a pillar lamp for motor vehicle bodies, as shown.

HAROLD B. DONLEY.
